UNITED STATES PATENT OFFICE

WALTER DRAPER, OF CHORLEY, ENGLAND

DRAWING OR DRAFTING ROLLER FOR TEXTILE-SPINNING MACHINERY

Application filed August 27, 1929, Serial No. 388,703, and in Great Britain February 7, 1929.

This invention has reference to textile spinning machinery and particularly to machinery used in the spinning of fibrous materials, where drawing or drafting takes place, examples of such machines as used in cotton spinning being those known as derbys, ribbon lap machines, combers, draw, slubbing, intermediate, roving or jack and ring frames, and mules.

10 The object of drawing or drafting is to straighten and align the fibres of the material such as cotton sliver or roving, and to cause them to slide over one another, thus elongating and attenuating the sliver. The ultimate 15 aim of all spinning operations is to produce a yarn which is strong and uniform. In the course of manufacture the sliver passes through a number of consecutive processes before it becomes the finished yarn, and in 20 many of these drafting is a feature. It is therefore of the utmost importance that drawing or drafting should be carried out in such a way as to yield a uniform material, without weak or thin places and also that the process 25 employed should be capable of yielding a satisfactory yarn.

I have established that if both top and bottom rollers in the line immediately behind the delivery or front rollers are made plain 30 and smooth of polished metal and the weight of the top roller also having these characteristics is proportioned so as to hold the sliver firmly between the two rollers without any nip, a remarkable improvement takes place in 35 the drafting results when the other bottom lines of rollers are fluted.

According to my invention as applied to a three line system, I use for the back and front rollers the usual rollers i. e. a fluted 40 bottom roller and a smooth or fluted top roller. It is necessary that a definite nip should be applied to the sliver at these points thereby isolating a portion of sliver both for feed and delivery purposes and also to avoid the communication back to the sliver of twisting 45 which is taking place in a subsequent stage of the operations. But for the middle rollers I employ an unfluted bottom roller of smooth and polished metal in conjunction with an unfluted top roller having the same character-

istics and of sufficient weight to give a firm hold to the cotton sliver without nipping or locking any of the fibres.

The top rollers of the middle lines must consequently be of considerable weight compared to the very light rollers recently suggested and in use. Their exact weight will in every case depend on the cotton used and the stage of the process, and it will be readily understood that it is not possible to lay down any figure of weight and size except by way of example but it is easy to ascertain this by trial in any given case if it is borne in mind that the object is to hold the sliver firmly without nipping it, so as to obtain a uniform and strong yarn. As a rule a lighter top middle roller will be suitable for fine counts and a heavier for the more coarse counts.

By the use of such rollers the sliver is evenly controlled by both rollers and the front 70 rollers are therefore enabled to maintain an even draft on all the fibres. This arrangement obviates the unevenness of pull which I believe to be the main defect in the existing 75 systems where the bottom roller is fluted and the top plain, because in the latter case as I have found by experiment there is a strong 80 tendency for the top fibres to move forward while the bottom fibres are locked by the projections. Moreover my invention obviates any necessity for aprons, and, while not reproducing any of their disadvantages, produces as good or better results.

In the accompanying drawing is shown a conventional end view of three lines of rollers, showing the application of the invention 85 thereto.

In the drawing the bottom front or delivery roller which is fluted is marked A and the top front or delivery roller is marked D. The 90 bottom middle roller B is according to this invention a plain or smooth non-fluted roller and its top roller is marked E. The bottom back or feed roller C is fluted as usual and co-operates with the top back feed roller F. 95 In the drawing the roller settings, that is the distances between the rollers are indicated by the letters G and H which respectively represent the distances between the bottom lines of rollers A and B and B and C.

The following tabulated statement indicates the sizes, weight and settings of rollers that have been found highly efficient in spinning cotton of the kind and staple set out in the first column of the table, but it is to be understood that suitable adjustments may be necessary, which it is within the skill and knowledge of a competent spinner to make according to particular conditions for which allowance would have to be made when using existing spinning methods. As an indication of adjustments which may be required the following information is given.

(1) Where closer settings are required for shorter stapled cottons than those given below the diameter of the middle rollers B and E may be reduced.

(2) The weights of the top rollers will vary according to the diameter of the rollers, and when using the invention on a spinning mule, if a roller of $\frac{3}{4}$ " diameter be used the weight should be from $3\frac{1}{2}$ to 4 ozs. and generally it will be found more convenient to use a lighter top roller on a mule than in a ring frame.

Cotton	Diamrs. of bottom rollers			Diamrs. of top rollers			Roller settings		Weight of top rollers		
	A	B	C	D	E	F	G	H	D	E	F
Egyptian (Sakel) $1\frac{1}{2}$ " staple	Inches	Inches	Inches	Inches	Inches	Inches	Inches	Inches	5 oz. appr.	2 lbs. 2 oz. appr.	
	1	$\frac{1}{2}$	1	$1\frac{1}{2}$	$\frac{3}{4}$	$1\frac{1}{4}$	$\frac{1}{2}$	$1\frac{1}{8}$			
Egyptian (Uppers) $1\frac{1}{4}$ " staple	1	$\frac{1}{2}$	1	1	$\frac{3}{4}$	2	$\frac{1}{2}$	$1\frac{1}{8}$	5 oz. appr.	3 lbs. appr.	
American (Memphis) $1\frac{1}{4}$ " staple	1	$\frac{1}{2}$	1	$1\frac{1}{2}$	$\frac{3}{4}$	$1\frac{1}{4}$	$\frac{1}{2}$	$1\frac{1}{8}$	5 oz. appr.	2 lbs. 2 oz. appr.	
American (Memphis) $1\frac{1}{4}$ " staple	1	$\frac{1}{2}$	1	$1\frac{1}{2}$	$\frac{3}{4}$	$1\frac{1}{4}$	$\frac{1}{2}$	$1\frac{1}{8}$	5 oz. appr.	2 lbs. 2 oz. appr.	

What I claim as my invention and desire to secure by Letters Patent is:—

A drawing head for a textile spinning machine having fluted bottom rollers at the back and front and having a bottom roller immediately behind the front delivery roller, unfluted and made of smooth polished metal, the top roller corresponding therewith having the same characteristics and being of such a weight as to hold the roving or sliver firmly against the bottom roller and against the draft of the front rollers, the diameters of the smooth bottom and top rollers being approximately as thirteen sixteenths is to three quarters, and the top rollers weighing 5 ozs.

In testimony whereof I have signed my name to this specification.

WALTER DRAPER.
